DISCHARGE PORT FOR ICE CREAM CABINETS

Filed Dec. 15, 1922

Inventor:
Charles Nelson.

by Oscar A. Michel,
Attorney.

UNITED STATES PATENT OFFICE.

CHARLES NELSON, OF ST. LOUIS, MISSOURI, ASSIGNOR TO C. NELSON MANUFACTURING COMPANY, OF ST. LOUIS, MISSOURI, A CORPORATION OF MISSOURI.

DISCHARGE PORT FOR ICE-CREAM CABINETS.

Application filed December 15, 1922. Serial No. 607,261.

To all whom it may concern:

Be it known that I, CHARLES NELSON, a citizen of the United States, residing at the city of St. Louis and State of Missouri, have invented new and useful Improvements in Discharge Ports for Ice-Cream Cabinets, of which the following is a specification, reference being had to the accompanying drawings.

10 My invention relates to discharge ports of ice cabinets and has for its object to provide a discharge and closed port in relation near the bottom of the ice cabinet, wherefrom the accumulated liquid sediments can be fully drained to prevent the overflow of the water and to remove other obstructions.

Another object of my invention is to provide a device of the character indicated, 20 having novel means for adjusting the sections of the device in unison from a central point, thus making it convenient to shift the parts to suit the requirements as indicated.

25 Various other objects and advantages will be brought out in the following specific description of the present preferred embodiment of this invention, the same being illustrated in the accompanying drawing wherein,

Figure 1 is a plan view of the device constructed according to my invention;

Figure 2 is a longitudinal sectional view of the same on the line 2-2 of Figure 1;

30 Figure 3 a detached bottom view of the check-arm, and

Figure 4 a vertical section on the line 4-4 of Figure 1.

In the drawing the numeral 1 represents 40 the section of the side holding portion of an ice cabinet, having at its intermediate marginal lower edge a central bore 2 to receive a cylindrical stationary member 3. Integral with said member 3 and positioned

45 within the inner surface of the frame member 1 is an abutting nut 4, compressively engaging the frame portion 1 by means of the resilient washer 5 and the internally threaded nut 6. Integral with said nut 6 50 is a check arm 7 engaging the externally threaded end portion of the stationary member 3 for a horizontal adjustment with the check arm 7.

The point of termination in the range 55 of movement of the two sections 3 and 7 is

at the abutting line 8 of the two terminal inner ends of the sections 3 and 7. The check arm 7 is of cylindrical construction, and when in composite operation with the stationary member 3 has its central bore in 60 aligned relationship with the central bore of the member 3.

Positioned about midway at the bottom of the check arm 7 is a discharge orifice 9 with a restricted outlet and in co-operative 65 communication with the central bore of the stationary member 3. Mounted on the peripheral terminal of the check arm 7 are threaded extensions 10 and 11 to engage in mesh the threaded components 10' and 11' 70 of the wedge collar 12.

The cup shaped wedge collar 12, concentrically mounted and in embracing relation, when in operative engagement with the check arm 7, is fully movable to assume different relationship to each other and is adapted by its rotational movement, either rearwardly or forwardly to open or close the discharge port 9, making the two structural sections 7 and 12 mutually 75 reciprocable with reference to each other.

It is obvious that the discharge port 9 in operative relation with the wedge collar 12 will allow the accumulated liquid contents in the ice cabinet to pass through the restricted outlet 9 and any collective obstructions from the inner housing of the cabinet 1 at the mouth of the central bore of the stationary member 3 can be removed by manual means either through the discharge port 9 or the open end of the central bore in the check arm 7.

Although but one specific embodiment of this invention has been herein shown and described, it will be understood that 95 numerous details of the construction shown may be altered or omitted without departing from the spirit of this invention as defined by the following claims.

What I claim as new is:—

1. In a new article of manufacture, the combination with a receptacle having an entrance orifice therein, a stationary carrying member, having one portion adapted to be connected with said orifice in the receptacle, a plurality of interchangeable units, comprising a series of tubular sections of circular cross-sectional shape in operative engagement and disengagement with said carrying member, one of said sections ad- 110

jacent to the carrying member having a discharge port for exhausting liquid deposits in said cabinet therefrom, a wedge collar in embracing relation with said discharge section, means for detachably engaging and disengaging said wedge collar and the discharge section.

2. In an ice cabinet, the combination with a receptacle having an entrance orifice therein, a stationary carrying member, rigidly engaging said orifice in the receptacle in combination with an operating member adapted to move into and out of operative position, comprising a series of detachable members, one of said members being in operative alignment with said carrying member, motive means carried on said detachable member, and means for positioning said motive means differentially.
3. In an implement of the class described, a discharging element, composed of aligned sections, one of said sections being adapted

for insertion into a body portion, fastening means for rigidly holding said section in operative engagement with said body portion, an auxiliary member, mounted adjacent and in operative alignment with said section, comprising by means of screw threaded terminals one unit, an outlet port in the bottom of said auxiliary section, a skirt element engaging said auxiliary member in open or closed position.

4. In a new article of manufacture, the combination with a discharge element, an auxiliary member mounted adjacent and in operative alignment with said discharge element, an outlet in the bottom of said auxiliary member, a skirt element engaging said auxiliary member in open or closed position.

In testimony whereof I hereunto affix my signature.

CHARLES NELSON.
